INVENTOR.

UNITED STATES PATENT OFFICE.

ZECHARIAH R. TUCKER, OF PROVIDENCE, RHODE ISLAND.

MEASURING INSTRUMENT.

953,933.

Specification of Letters Patent. Patented Apr. 5, 1910.

Application filed May 12, 1909. Serial No. 495,462.

To all whom it may concern:

Be it known that I, ZECHARIAH R. TUCKER, a citizen of the United States, residing at Providence, in the county of Providence and State of Rhode Island, have invented 5 certain new and useful Improvements in Measuring Instruments, of which the following is a specification.

My invention relates to micrometric measuring instruments adapted for use as height 10 or depth gages, and calipers, and is designed to provide an instrument which shall have a measuring capacity in excess of the graduated area of the structure, and which will 15 enable the operator to employ any desired measuring unit, and to attain this end in a compactly arranged structure.

The invention consists in producing the results above specified substantially as hereinafter claimed.

In the accompanying drawings which 20 form a part of this specification, Figure 1, is a side elevation of a pair of micrometer calipers embodying my invention, Fig. 2, a 25 similar elevation of the same partially in central longitudinal section, Figs. 3 and 4, rear and front end elevations respectively of the same, and Fig. 5 a section on line 5—5 of Fig. 2.

30 In the views similar characters of reference indicate like parts throughout.

In the preferred construction 1 represents a bar of cylindrical or other cross section, to one end of which is fixed by a pin 2 or otherwise a jaw 3 which jaw if preferred may be 35 removably connected with the bar. In the present instance the jaw has an end bearing face 4.

40 Loose upon the bar 1 is a barrel 5 with an exterior micrometric scale 6 and whose inner end forms the base of an integral jaw 7 having an end bearing face 8. In a threaded opening 9 in the barrel is a set screw 10 whose pointed end 11 registers in a groove 45 12, extending longitudinally of the bar 1. The interior of the barrel 5 is bored out a major portion of its length to form an internal abutment 14 at its inner end and an annular space around the bar 1. The 50 interior of the outer end of the barrel 5 is provided with threads 16 engaging the threads 17 of a hollow micrometer screw 18 carrying the usual measuring thimble 19 with its scale 20. Obviously if desired the usual 55 micrometer nut may be introduced between the barrel 5 and the screw 18.

Slidably mounted upon the bar 1 in contact with the hollow interior face of the screw 18 is a sliding member which in this instance consists of a sleeve or bushing 21 provided upon the exterior of its inner end with an annular projection or collar 22 and having an opening 23 to receive a screw 24 whose point 25 loosely extends into the groove 12 to prevent the sleeve 21 from rotary movement. It will be understood that a spline or other well known element may be used for this purpose. The outer end of the sleeve has exterior threads 26 and is longitudinally split as at 27, to form integral 70 clamping fingers or segments 28, engaged by a clamping nut 29 whose threads 30 engage threads 26. When the nut 29 is tightened it holds the sleeve 21 fast to bar 1, and when loosened, releases the bar 1.

The parts 5, 7, 18, and 19 which comprise an ordinary micrometer frame may be modified in any usual convenient manner. For the screw 10 which clamps this frame to the bar and holds the latter against rotation any 80 other convenient clamping means may be substituted.

The operation of my device is as follows. The thimble 19 is turned until its dial 20 reaches upon the scale 6 the graduation indicative of the space or measurement which it is understood shall constitute the unit of measurement to be employed in each particular instance. The screw 10 and nut 29 being loosened, the frame and sleeve 21 are 90 moved to the left or inwardly until the bearing faces 4 and 8 contact with each other, the shouldered end of sleeve 21 contacting with the abutment 14. The screw 10 is now tightened, and the sleeve 21 is outwardly moved until its shoulder 22 abuts against the end of screw 18, whereupon the nut 29 is tightened. Then the screw 10 is loosened and the frame is moved outwardly until its abutment 14 rests against the end of sleeve 21, whereupon the screw is again tightened. The space between the bearing faces 4 and 8 will now be equal to the unit of measurement indicated upon the barrel 5. The measurements may be indefinitely increased by 105 the described alternating outward movement of the frame and sleeve 21. Fractional measurements may be obtained by employing the dial 20 and scale 6 in the manner usual in micrometer calipers.

110 By removing the jaw 3 it is obvious that my device may be conveniently used as a

depth gage. When used as a height gage the shape of jaw 3 is preferably changed somewhat to form a more stable base.

What I claim is,—

5 1. In a measuring instrument, the combination with the frame, of a threadless measuring bar within the frame and arranged to slide longitudinally thereof, and a sliding member within the frame mounted 10 for longitudinal movement upon the bar.

2. In a measuring instrument, the combination with the frame, of a non rotary measuring bar within the frame and arranged to slide longitudinally thereof, a 15 sliding member within the frame mounted for longitudinal movement upon the bar, and means adjustably clamping the sliding member.

3. In a measuring instrument, the combination with the frame, of a measuring bar 20 slidably mounted in the frame, a sleeve slidably mounted upon the bar and in slidable contact with the interior of the frame, and means upon the sleeve within the barrel for 25 limiting the movement of the sleeve.

4. In a measuring instrument, the combination with the frame, of a measuring bar 30 slidably mounted in the frame, a slideable sleeve upon the bar intermediate the frame and bar, and clamping means upon the sleeve.

5. In a measuring instrument, the combination with a frame, of a measuring bar 35 slidably mounted in the frame, a sleeve slidably mounted within the frame and upon the bar, and means upon the sleeve for limiting the movement of the sleeve upon the bar.

6. In a measuring instrument, the combination with a frame, of a measuring bar 40 within the frame and arranged to slide longitudinally thereof, a sleeve slidably mount-

ed on the bar within the frame and provided at one end with an annular shoulder in the path of the frame, and clamping means upon the other end of the sleeve. 45

7. In a measuring instrument, the combination with the frame, of a measuring bar 50 slidably mounted in the frame, a sliding member upon the bar, and means upon the sliding member for clamping the bar to the sliding member.

8. In a measuring instrument, the combination with a frame, of a measuring bar 55 within the frame and arranged to slide longitudinally thereof, a sleeve slidably mounted on the bar within the frame and provided with a shoulder in the path of the frame, and provided with spring fingers, and a clamping nut upon the fingers. 55

9. In a measuring instrument, the combination with a frame, of a measuring bar 60 slidably mounted in the frame and provided with a longitudinal groove, a jaw upon the bar, a slideable member upon the bar, means for clamping the slideable member to the bar, 65 a screw in the frame entering the slot in the bar, and a screw in the slideable member registering in said groove.

10. In a measuring instrument, the combination with a frame, of a measuring bar 70 slidably mounted in the frame, a jaw upon the bar, a sleeve slidably mounted upon the bar, means upon the sleeve and engaging the bar to prevent rotary movement of the sleeve, and means upon the frame for preventing rotary movement of the bar. 75

In testimony whereof I have affixed my signature in presence of two witnesses.

ZECHARIAH R. TUCKER.
